UNITED STATES PATENT OFFICE.

JONATHAN H. REA, OF OMAHA, NEBRASKA.

AEROPLANE.

1,398,466.

Specification of Letters Patent. Patented Nov. 29, 1921.

Application filed January 17, 1921. Serial No. 438,042.

To all whom it may concern:

Be it known that I, JONATHAN H. REA, citizen of the United States, residing at Omaha, in the county of Douglas and State 5 of Nebraska, have invented certain new and useful Improvements in Aeroplanes, of which the following is a specification.

The present invention relates to improvements in aeroplanes or aircraft, and has for 10 an object to provide an arrangement of supporting planes that will act in the capacity of a parachute should the motor become stalled while in the air.

It is another object of the invention to 15 provide improved driving and lifting propellers arranged to be driven from a common source of power through independent connections arranged to be individually controlled.

20 A further object of the invention is to provide an improved running gear having an upwardly curved guard extending in advance of such running gear for encountering the ground when the aeroplane is landing to avoid the "digging in" of the same.

25 A further object of the invention is to provide a simple and inexpensive construction of aeroplane having its parts compactly grouped together.

30 With the foregoing and other objects in view, the invention will be more fully described hereinafter, and will be more particularly pointed out in the claims appended hereto.

35 In the drawings, wherein like symbols refer to like or corresponding parts throughout the several views,

Figure 1 is a side elevation with a portion broken away of an aeroplane constructed in accordance with the present invention;

Fig. 2 is a front elevation thereof; and Fig. 3 is a rear elevation of the same.

Referring more particularly to the drawings, 45 5 and 6 designate a pair of sustaining planes constructed in any suitable approved fashion and being of the required area to support the necessary load. These planes 5 and 6 are arranged in a peculiar formation as disclosed more particularly in Figs. 2 and 3. The planes at their upper ends converge and meet forming a substantially acute angle and providing a space within the planes open at both front and rear ends 55 for receiving the air which reacts on the in-

terior surfaces of the planes 5 and 6 to support the aircraft.

A number of braces 7 are disposed diagonally of the aeroplane at the base of the planes 5 and 6 and are used to connect 60 and hold apart the lower divergent ends of such planes. The planes and braces are held upon a suitable running gear which is made up in the instance shown of front supporting ground wheels 8 connected by rods 9 65 and 10 with the bottom portion of the fuselage.

A guard 11 extends between the two front wheels 8 and has an upwardly curved end carried in advance of the running gear and 70 at a low elevation so as to encounter the ground especially in landing to avoid the "digging in" of the aeroplane. A brace rod 12 is connected between the guard 11 and the rod 9. 75

At the rear the aeroplane is supported upon a caster wheel 13 held in a fork 14 which is swivelly mounted at the base of the aeroplane.

80 A motor 15 is installed on the braces held substantially amidships and at a low level in order to maintain the weight at a low point and lower the center of gravity as much as practicable. The motor 15 is provided with shafts 16 and 17 projecting from 85 both ends thereof and entering transmission boxes 18 and 19 respectively.

90 Gear shift levers 20 and 21 control the transmission gears within the boxes 18 and 19. The transmission box 19 is arranged in connection with a drive shaft 22 extending forwardly and carrying a pulley 23 engaged by a belt 24 which also runs over an upper pulley 25 on the shaft 26 of the driving propeller 27. This driving propeller 27 is supported forwardly of the space between the planes 5 and 6 and acts as a traction propeller drawing the plane forwardly in a horizontal direction. 95

100 The other clutch box 18 is connected to a drive shaft 28 having a pinion 29 meshing with a second pinion 30 on a vertically disposed shaft 31. A pulley 32 near the upper end of the shaft 31 connects with a belt 33 turning a pulley 34 on a second vertical shaft 105 35 carried thereby. This latter shaft extends upwardly through the aeroplane and carries a lifting propeller or helicopter 36.

110 A rudder 37 is mounted at the rear of the aeroplane and is controlled by a hand wheel

38 and by a cable 39 moved by such hand wheel 38. Elevators 40 are also supported at the rear end of the aeroplane and are controlled by a hand wheel 41 which operates a 5 cable 42 connected at opposite ends to arms 43 and 44 carried by such elevators.

In use the motor 15 may act through the transmission 18 to drive the lifting propeller 36 by which the machine may be elevated a 10 desired distance. This elevation of the machine may occur together with its forward driving by the action of the front propeller 37. Either of these propellers may be disconnected through the gear shift levers 20 15 and 21. The hand wheels 38 and 41 are disposed close together and near the lever 21 so that the controlling parts are compactly assembled and may be easily manipulated from the space within the planes 5 and 6. 20

20 Should the engine 15 become stalled while in the air the triangular space within the planes 5 and 6 will form a pocket for the air and will have a sustaining effect similar to a 25 parachute so as to break the fall of the aeroplane.

I do not wish to be restricted to the size, form, and proportions of the various parts, and obviously changes could be made in the construction herein described without de- 30 parting from the spirit of the invention, it being only necessary that such changes fall within the scope of the appended claims.

What is claimed is:

1. An aeroplane comprising a pair of co- 35 operating planes running longitudinally of the aeroplane and having their upper ends secured close together at a substantially acute angle and parallel with the longitudinal axis of the aeroplane, said planes diverging downwardly, the lower edges of such 40 planes lying at the outermost sides of the aeroplane, said planes providing a substantially triangular space therewithin open at

its front and rear ends and also at its bottom, braces extending in spaced relation 45 transversely across the bottom of said space and secured to the lower divergent edges of said planes, a propeller forwardly of said planes and directly in front of the space between said planes, steering mechanism opposite of the space between said planes and directly in rear of such space to receive air currents passing therethrough, and a horizontally turning helicopter propeller lying above the central portions of the planes and 50 adapted to direct streams of air downwardly on the opposite divergent surfaces of the planes. 55

2. An aeroplane comprising a pair of planes secured together at their upper edges 60 at a substantially acute angle and extending longitudinally of the aeroplane with their lower edges arranged at the outermost sides of the aeroplane whereby said planes are disposed in triangular divergent relation 65 having a substantially triangular space therewithin, transverse braces extending in spaced relation between the lower edges of said planes, running gears supporting said planes, a tractor propeller at the 70 front of the aeroplane directly in advance of the space within said planes, steering and elevating apparatus directly in rear of the space between said planes, a horizontally turning helicopter propeller supported above 75 the meeting tops of said planes, and a power plant supported within the space between said planes and having connection to drive said tractor propeller and helicopter.

In testimony whereof, I have affixed my 80 signature in presence of two witnesses.

JONATHAN H. REA.
